UNITED STATES PATENT OFFICE.

EDWARD P. FREDERICK AND HENRY NIEMEIER, OF ST. LOUIS, MISSOURI, ASSIGNORS
TO JOSEPH D. BASCOM, OF ST. LOUIS, MISSOURI.

WIRE-ROPE CLAMP.

1,117,656.

Specification of Letters Patent. Patented Nov. 17, 1914.

Application filed March 10, 1913. Serial No. 753,146.

To all whom it may concern:

Be it known that we, EDWARD P. FREDERICK and HENRY NIEMEIER, citizens of the United States, residing in the city of St. Louis and State of Missouri, have invented certain new and useful Improvements in Wire-Rope Clamps, of which the following is a specification.

This invention relates to attachments for ropes, cables, and the like, and has for its object to provide an improved clamp, which is adapted to hold the end of a rope, cable, or the like, and is designed so that a draft-hook or any other device can be attached thereto, the same being particularly well adapted for use in connection with the tow-line, which is disclosed in United States Letters Patent, No. 1,009,633, granted to Joseph D. Bascom, November 21, 1911.

Further, the present invention consists of the novel features of construction and arrangement of parts hereinafter more fully described and pointed out in the claims.

In the accompanying drawings forming part of this specification, in which like numbers of reference denote like parts wherever they occur, Figure 1 is a perspective view of a clamp embodying the present invention, showing same holding an end of a rope and having a draft-hook attached thereto; Fig. 2 is a side elevation of the clamp with the draft-hook detached therefrom; Fig. 3 is an interior plan view of one of the parts of the clamp; Fig. 4 is an interior perspective view of the other part of the clamp; Fig. 5 is a sectional view on the line 5—5, Fig. 1; Figs. 6 to 9, inclusive, are detailed views of an alternate form of the invention; and Fig. 10 is a sectional view on the line 10—10, Fig. 6.

The clamp consists of two members 1 and 2, which members are preferably formed with somewhat of an elliptical configuration and are fastened together by means of a bolt 3 or the like, said bolt extending through openings 4 in approximately the centers of said members. The member 1 is relatively longer than the member 2 and bears a lug 5, which projects from the inner face of said member 1 at one end thereof, the end face of the lug 5 being flush with the end face of the member 1, and the inner face 6 of said lug being preferably arranged to slope so as to hold the beveled end 7 of the member 2 in place, thereby preventing the

end of the member 2 from projecting above the outer surface of said lug. A lug or projection 2^a on the beveled end 7 of the member 2 seats in a notch 1^a in the lug 5 and thereby prevents lateral movement of one member with respect to the other. An opening 8 is preferably formed partly in the end of the member 1 that bears the lug 3 and partly in said lug, so that its axis substantially coincides with the longitudinal axis of the clamp, and is of such size that the end of a rope or cable 9 to be clamped can pass therethrough, said rope or cable being preferably formed of wire. Grooves 10 and 11 in the inner faces of the members 1 and 2, respectively, register with each other and unite to form somewhat of an elliptical-shaped space, which communicates with the opening 8 for the purpose now to be described.

The rope or cable 9 is passed through the opening 8 in the member 1 and is then formed in a loop 12 to fit in the groove 10 in said member, after which the end of the rope or cable is secured to the main part 80 thereof by wire seizing 13 or other suitable means. The member 2 is then placed with its inner face covering the inner face of the member 1 so that the part of the loop 12 that projects from the groove 10 in member 1 will seat in the groove 11 in the member 2, and the beveled end 7 of the member 2 underlies the sloping face 6 of the lug 5 on member 1, whereupon the bolt 3 is passed through the openings 4 in the members 1 85 and 2 and the nut thereon tightened, thereby holding said members securely together, and, also, causing said members to clamp and hold the loop 12 firmly in the grooves 10 and 11. It will be observed that the bolt 3 95 extends through approximately the center of the loop 12, an object of this arrangement being to cause the members 1 and 2 to exert substantially a uniform pressure upon the whole loop 12, so as to hold the latter 100 securely in the grooves 10 and 11.

The ends of the members 1 and 2 that extend beyond the loop 12 have openings 14 extending transversely therethrough, which openings register with each other so as to 105 receive a bolt or pin 15 for the purpose of attaching a clevis 16 or the like to the ends of said members. Said clevis may pass through the eye 17 of a draft-hook 18 or may have anything else attached thereto. 110

It will be observed that the axis of the opening 8 passes through the axes of the bolts 3 and 15, so that said bolts will be directly in line with the pull on the rope or cable 9, the advantage of this arrangement being obvious.

In the alternate form of the invention depicted in Figs. 6 to 10, inclusive, the member 2 is relatively shorter and is adapted to fit between the lug 5 at one end of the member 1 and the lug 19 at the other end of said member 1, the inner face of said lug 5 being preferably substantially perpendicular to the inner face of the member 1, instead of sloping as hereinabove described, and the lug 19 being arranged to project from the inner face of the member 1 beyond the loop 12 and being provided with a notch 20 to receive a lug or projection 21 borne by the end of the member 2 adjacent thereto. By this arrangement, the lugs or projections 2^a and 21 on the ends of the member 2, by seating in the notches 1^a and 20 in the lugs 5 and 19, respectively, borne by the member 1, prevents lateral movement of one member with respect to the other. The opening 14 is omitted entirely from the member 2, and the opening 14 in the member 1 is arranged to extend also through the lug 19, as best seen in Fig. 10.

It will be evident that a rope clamp constructed as hereinabove described will be strong and efficient and, furthermore, same will be simple, easy, and inexpensive to manufacture.

We claim:

1. A rope clamp comprising two members having grooves in their inner faces, which grooves register with each other and unite to form a space to receive the looped end of a rope, one of said members being relatively longer than the other and bearing a lug, which projects from the inner face of the same at one end thereof, there being an opening partly in the end of the longer member that bears the lug and partly in said lug, which opening communicates with the grooves in said members and is adapted to receive the main part of the rope, and means connecting said members and so situated as to pass through the looped end of the rope for clamping the latter in the grooves in said members.

2. A rope clamp comprising two members having grooves in their inner faces, which grooves register with each other and unite to form a space to receive the looped end of a rope, one of said members being relatively longer than the other and bearing a lug, which projects from the inner face of the same at one end thereof, there being an opening partly in the end of the longer member that bears the lug and partly in said lug, which opening communicates with the grooves in said members and is adapted

to receive the main part of the rope, and means connecting said members and so situated as to pass through the looped end of the rope for clamping the latter in the grooves in said members, the inner face of said lug 70 being arranged to slope and the end of the shorter member adjacent thereto being beveled to underlie the same.

3. A rope clamp comprising two members having grooves in their inner faces, which 75 grooves register with each other and unite to form a space to receive the looped end of a rope, there being an opening in an end of one of said members which communicates with the grooves in said members and is adapted to receive the main part of the rope, means connecting said members and so situated as to pass through the looped end of the rope for clamping the latter in the grooves in said members, the ends of said 80 members extending beyond the grooves which are adapted to contain the looped end of the rope, and means connecting such extensions.

4. A rope clamp comprising two members 90 having grooves in their inner faces, which grooves register with each other and unite to form a space to receive the looped end of a rope, there being an opening in an end of one of said members which communicates 95 with the grooves in said members and is adapted to receive the main part of the rope, means connecting said members and so situated as to pass through the looped end of the rope for clamping the latter in the 100 grooves in said members, the ends of said members extending beyond the grooves which are adapted to contain the looped end of the rope, means connecting such extensions, and a member secured to said last- 105 mentioned connecting means.

5. In combination with a rope having a looped end and a draft attachment, a clamp including two members having grooves in their inner faces, which grooves register 110 with each other and unite to form a space to receive the looped end of the rope, there being an opening in an end of one of said members which communicates with the grooves in said members and is adapted to 115 receive the main part of the rope, means connecting said members and so situated as to pass through the looped end of the rope for clamping the latter in the grooves in said members, and means for attaching the draft 120 attachment to the ends of said members that extend beyond the looped end of the rope.

6. A rope clamp comprising two members having grooves in their inner faces, one end of one member being enlarged to extend beyond the inner face of said member and being perforated to admit the rope, said enlargement being notched on its inner end, the other member having a lug on one end thereof which is received in said notch, 125 130

means to hold the opposite ends of the members against relative lateral movement, and means extending through the centers of the members to connect the members.

5 7. A rope clamp including a member having an enlarged end which is provided with an opening to admit an end of a rope, a second member which seats on the inner face of the first member and has one end 10 thereof abutting the inner end of the enlargement of the end of the first named member, means to lock said members against transverse movement at their abutting points, said members having grooves on 15 their inner faces to receive a loop into which the said rope end is formed, and means passing transversely through the members to secure the latter together.

8. A rope clamp including a member having one end thereof provided with a single opening which forms an endless bounding wall to admit an end of a rope by inserting 20 said rope end in the front end of the opening, a second member which seats on the inner face of the first named member, the first 25 named member having a substantially ellip-

tical groove on its inner face to receive a loop into which the said rope end is formed, said single opening of the first named member leading into one end of the elliptical 30 groove so as to be common to both sides of said groove, and means to connect the members.

9. A rope clamp including two members placed one on top of the other having 35 grooves on their inner faces which register and unite to form a space to receive the looped end of a rope, a projection borne by one of the members and having a perforation which registers with one of said grooves 40 and is adapted to receive the main part of the rope and means to connect the members so as to hold the looped end of the rope in said registering grooves.

In testimony whereof we hereunto affix 45 our signatures in the presence of two witnesses:

EDWARD P. FREDERICK.
HENRY NIEMEIER.
